United States Patent Office.

CHARLES G. MARSHALL, OF FLORENCE, MASSACHUSETTS.

Letters Patent No. 65,924, dated June 18, 1867.

IMPROVED MODE OF FORMING EMERY-WHEELS.

The Schedule referred to in these Letters Patent and making part of the same.

TO ALL WHOM IT MAY CONCERN:

Be it known that I, CHARLES G. MARSHALL, of Florence, Hampshire county, Commonwealth of Massachusetts, have invented certain new and useful improvements in Emery-Wheels; and I do hereby declare that the following is a full and exact description thereof.

This invention consists of a new and improved combination of materials forming the wheel, whereby it is rendered more perfect in its operation.

The material from which my emery-wheel is formed consists of the following ingredients, put together as I will now describe: Ordinary glue is dissolved in water, so as to make a somewhat thick solution; with this is mixed the emery powder, and also about an equal quantity of concrete lime. These are mixed into a consistency sufficient to hold it together, and are then placed under dies formed of the proper shape and size to produce the required wheel. These are placed under a hammer, which, by its force, presses the materials into a solid form, making the emery-wheel. The lime forms a hard cement with the glue around all the particles of emery, holding them together in a solid bed.

By these means I obtain an emery-wheel far superior to those ordinarily in use, in that it is much more solid, and being thoroughly mixed before being formed, the materials composing it are equally solid at any part, causing it to wear evenly.

It is not absolutely necessary to use the glue in this composition, as the cement may be made to answer both purposes.

Now, having described my invention, what I claim as new, and desire to secure by Letters Patent, is—
The use of concrete lime or cement in the formation of emery-wheels, substantially as and for the purpose herein set forth.
